CONTACT-MAKING DEVICE FOR
ELECTRICAL APPLIANCES

Henri Louis Lesigne, Vanves, France

Application September 19, 1945, Serial No. 617,377
In France February 5, 1941

6 Claims. (Cl. 200—166)

1

The present invention relates to contact-making devices as used on miscellaneous electrical appliances for making, breaking or switching purposes and has more particular reference to make and break devices used on circuits through which weak currents flow such for instance as remote control circuits.

The primary object of the present invention is to provide a contact-making device of improved and simple structure made up of a minimum number of parts capable of being manufactured easily and at a low cost.

Another object of the present invention is to provide a contact-making device comprising in combination a blade contact member having a smooth contact surface and a companion blade contact member having a brush-like contact surface made up of short stiff wires or metal filaments and capable of being brought into contact with said smooth surface.

Other objects of the invention will appear from the following description and from the accompanying drawing exemplifying the same and forming a part of the present disclosure, said drawing representing in Figures 1 to 4 suitable constructional forms of the invention as applied to relay blade-like terminals.

Fig. 1 shows an embodiment of the switch assembly of my invention wherein shoes or blocks are mounted on the inner face of both switch blades and on one shoe is mounted a contact brush consisting of many short wires extending substantially perpendicular to the shoe.

Fig. 2 shows an arrangement with two such shoes, but with the fine wires mounted on the one shoe extending at an acute angle thereto.

Fig. 3 shows an embodiment in which there is no shoe on the blade carrying the contacting fine wires, which are mounted directly on that blade itself, but the other blade does carry a shoe.

Fig. 4 shows an embodiment wherein the fine wires are directly mounted on the blade itself, and perpendicularly thereto, as in Fig. 3, but there is no contact shoe on the other blade.

Fig. 5 shows an embodiment wherein the fine wires are mounted directly on the blade itself, as in Fig. 4, but obliquely thereto, and there is no contact shoe on the other blade.

Fig. 6 shows an embodiment wherein the fine wires are mounted on a shoe, as in Fig. 1, but the contact shoe is omitted on the other blade, as in Fig. 4.

Fig. 7 shows in plan a switch blade member carrying a contact brush of many fine wires.

2

Fig. 8 shows, on an enlarged scale, the portion of the blade of Fig. 7, carrying the brush, and

Fig. 9 shows a simplified view of a telephone relay to which the switch and brush of the present invention have been applied.

In the drawings, 1 and 2 designate two blade-like contact elements of resilient nature normally separated by a gap and adapted to be moved as shown by the double arrows either for being brought together into closed position for permitting the electric current to flow from one blade member to the other or for being separated into open position.

In the constructional forms shown in Figs. 1 and 2, the blade members 1 and 2 are provided on their oppositely located inner surfaces with elongated and relatively thin blocks or shoes 4, 5 conductively fixed thereto. The shoe 4 is provided with a multiplicity of projecting wires or metal filaments 3 distributed throughout its area and forming a brush-like contact element, while the shoe 5 on the blade member 2 has a smooth free surface adapted to come into contact with the brush 3 for establishing the electric contact between the two blade members, for example responsive to a resilient distortion of the latter when they are pressed together.

In the form of Fig. 1, the metal filaments or wires 3 are mounted perpendicular to the shoe 4, while in the form of Fig. 2, the metal filaments or wires 3 are mounted oriented at an acute angle to the shoe 4.

The wires or metal filaments 3 should be short and fairly stiff to provide adequate electric contact when they touch the smooth surface of the shoe 5. Each wire 3 may be a single metal thread or a thin cable made up of two or more strands. Any suitable conductive metal or alloy may be used for making the wires 3, advantageously of a sufficient pliancy to permit them to adapt themselves into proper electric current-carrying contact with any unevenness of the cooperating smooth surface of the opposite shoe 4.

In the alternative constructional form shown in Figs. 3 and 4, the wires or metal filaments 3 may be directly carried by or fixed to the blade member 1 itself (for instance by welding or soldering) without the provision of a shoe such as 4. In such a constructional form, the companion blade terminal 2 may have a smooth surface shoe such as 5 (Fig. 3) or may be devoid of any such shoe (Fig. 4) in which case the blade member 2 itself is made adequately smooth for permitting proper electric contact.

In another alternative constructional form (shown in Fig. 6) the blade member 1 may have

a shoe such as 4 provided with a brush-like contact element 3, while the blade member 2 has no shoe such as 5 and is adequately smooth (if necessary polished or buffed) for providing proper electrically conductive contact with this brush.

No matter what constructional form of the device is adopted, the wires or metal filaments 3 of single or stranded character of which the contact brush is made up may extend at right angles (as shown in Figs. 1, 3 and 4) or at an oblique angle (as shown in Fig. 2) to the carrying surface of the associated blade member 1 or its shoe 4.

A contact-making device according to the invention may find its use on a wide range of electrical appliances, for example to switch or relay blade terminals, in which case the brush element is adapted to be brought into contact at a multiplicity of slightly spaced points with a facing shoe of contact block conductively secured to or cast integral with the companion blade member of the switch or relay.

Minor constructional details may be varied without departing from the scope of the subjoined claims.

What is claimed is:

1. In a switch device for weak currents, a pair of resilient blade members displaceably mounted in juxtaposition for controlled frequent to-and-fro mutually perpendicular movement into and out of resilient mutual engagement, a first one of said blade members having a smooth surface contact area, and a contact brush carried by the second said blade member and engageable with said contact area of said first blade member, said contact brush comprising a multiplicity of closely spaced, projecting, short, pliant, fine metal filaments distributed throughout its area and having projecting free ends projecting from the flat face of said second blade member and engageable with said contact area of said first blade member at a multiplicity of slightly spaced points thereof and adapted to

conform to any unevenness in the surface of said contact area.

2. A switch device, as set forth in claim 1, said fine filaments being soldered to said second blade member.

3. A switch device, as set forth in claim 1, and a terminal shoe carried by said second blade member, and said contact brush being carried by said shoe and its said filaments being distributed throughout the area of said shoe.

4. A switch device, as set forth in claim 1, and a first terminal shoe carried by said second blade member, and said contact brush being carried by said first shoe and its said filaments being distributed throughout the area of said shoe, and a second terminal shoe carried by said first blade member and constituting the smooth surface contact area thereof.

5. A switch device, as set forth in claim 1, said fine filaments of said contact brush extending substantially perpendicularly from said second blade member.

6. A switch as set forth in claim 1, said fine filaments of said contact brush extending substantially obliquely from said second blade member.

HENRI LOUIS LESIGNE.
